UNITED STATES PATENT OFFICE

EUGENE L. MESSLER AND JAMES M. GUTHRIE, OF PITTSBURGH, PENNSYLVANIA;
SAID GUTHRIE ASSIGNOR TO SAID MESSLER

CAP FOR HOT TOPS

Application filed May 9, 1929. Serial No. 361,620.

This invention relates to a refractory cap for use on ingot mold hot tops.

The general object of the invention is to provide a cap which will cover and largely close the bore opening at the upper end of the hot top, to conserve heat and thereby further delay solidification of metal in the hot top, thus further reducing the length of the sinkhead therein.

- 10 Another object of the invention is to provide a refractory cap arranged to cover the bore opening of the hot top, which has a portion extending downwardly into the bore of the hot top, which is free to be moved longitudinally in the bore, and which extends into the bore of the hot top a sufficient distance to be floated by molten metal in the hot top when the desired level of such metal has been reached in teeming.
- 20 Another object of the invention is to so contour the teeming orifice through the cap, and the lower metal contacting portion of the cap body that there is no surface presented upon which metal may solidify in such manner as to produce a hanging ingot.

In the accompanying drawings Figure I is a central vertical section through the simplest form of the refractory cap of the present invention, showing the same in position on a hot top; Figure II is a similar view of such simple form, but showing a greater downward extension of the cap to contact metal within the hot top at a lower level therein; and Figure III is a similar view of a modified form of hot top.

In the drawings the reference numeral 1 designates the ingot mold hot top, and the reference numeral 2 designates generally the refractory cap as shown in Figs. I and II.

- 40 Refractory cap 2 comprises a cover portion 3 provided with a seating shoulder 4 arranged to rest on the upper edge 5 of the hot top, to support the cap and cover the opening at the upper end of the bore 6 within the hot top. Extending downwardly into the bore of the hot top is a cap portion 7, which is lesser peripheral extent than the hot top bore in that region. While the cap is thus supported on the hot top by means of the seating shoulder 4, it is free to be

moved upwardly in the bore, and unseated from its position of rest on the hot top.

The teeming orifice 8 extends completely through the cap, and is disposed substantially centrally thereof. This orifice 8 is 55 desirably provided with an upper portion 9 the wall of which flares upwardly, or converges downwardly, to approximately the horizontal plane at the junction of the cover portion 3 and the downwardly extending portion 7 of the cap. In all figures of the drawings this horizontal plane is indicated by the reference numeral A. The lower portion 10 of the orifice is not so formed, but is shown in Figs. I and II as having 60 a wall equally spaced throughout the extent of this portion of the teeming orifice.

In the use of the hot top, the molten metal is teemed through the orifice 8, until it has filled the ingot mold with which the hot top 70 is used, and has risen into the body of the hot top. An indication as to the level which the molten metal has reached within the bore of the hot top is given by the refractory cap. As the downwardly extending portion 75 75 of the cap is loosely fitted in the hot top bore, the cap as a whole floats on the metal, and is lifted from its seat on the hot top, when the level of the metal in the bore of the hot top passes the lower surface of 80 the downwardly extending portion of the cap.

With different grades and composition of steel, it is desirable to have the metal extend different distances into the hot top, 85 these distances being in accordance with the characteristics of the metal itself, and the depth of segregated sinkhead which is to be anticipated within the bore of the hot top. For this reason the caps are provided 90 with downwardly extending portions of different length, in accordance with the desired level of metal in the hot top. The cap thus gives adequate warning when such desired level has been reached, as its unseating 95 movement is visible to those teeming the ingot.

When the ingot has been fully teemed, and the molten metal has risen the desired distance in the bore of the hot top, as indi- 100

cated by the unseating of the cap, pouring is immediately discontinued and cooling is permitted to take place. During the cooling of the metal, the cap floated thereby, 5 retards the dissipation of heat through the bore opening at the upper end of the hot top. This obviously contributes to the desired effect of a slow and gradual cooling of this portion of the metal, and further facilitates the escape of gas through this portion, 10 during the solidification of the ingot in the mold.

While the flared upper portion of the teeming orifice facilitates teeming, such flare 15 might present a surface on which the metal might solidify, thus tending to produce a hanging ingot. The floating of the cap prevents such occurrence, as the molten metal does not pass the straight portion 10 of the 20 teeming orifice in the downwardly extending portion 7 of the cap, this portion presenting no ledge upon which the metal may hang.

In the modification illustrated in Figure 25 III of the drawings, the refractory cap 2^a has a cover portion which itself seats within the body of the mold by means of an inclined shoulder 4^a engaging an inclined shoulder 4^b formed at the upper end of the hot top bore. While the cap rests upon the hot top in this manner the inclination of the shoulders permits the unseating of this cover portion.

The downwardly extending portion 7^a of 35 the cap in this modification also, does not fit the bore tightly, and is free so that the cap itself may be floated upwardly in the bore of the hot top. As shown, the lower surface 11 of this downwardly extending portion 7^a is curved. This curvature of the 40 surface provides additional protection against hanging ingots, in that it wholly avoids the possibility that metal may work in between the cap and the inner wall of 45 the hot top, to solidify therein in such manner as would tend to produce a hanging ingot. The curvature of this lower surface of the downwardly extending portion, as shown in Fig. III is continued into the lower portion 50 10^a of the teeming orifice 8^a. This form of the lower portion of the orifice facilitates removal of the cap from the metal without breakage, when the metal in contact with 55 the cap has become partially or wholly solidified.

What we claim is:

1. A refractory cap for ingot mold hot tops comprising a cover portion arranged to cover the bore opening at the upper end of 60 the hot top, a seating shoulder arranged to rest on the hot top, a portion arranged to extend downwardly a material distance from the upper end and into the bore of the hot top, and a teeming orifice extending 65 through both said cover portion and said

downwardly extending portion and disposed substantially centrally of both said portions.

2. A refractory cap for ingot mold hot tops comprising a cover portion arranged to cover the bore opening at the upper end of the hot top, a seating shoulder arranged to rest on the hot top, a portion arranged to extend downwardly a material distance from the upper end and into the bore of the hot top, said portion being so dimensioned horizontally relatively to the bore of the hot top as to be free to float on molten metal therein, and a teeming orifice extending through both said cover portion and said downwardly extending portion and disposed substantially centrally of both said portions. 70 75

3. A refractory cap for ingot mold hot tops comprising a cover portion arranged to cover the bore opening at the upper end of the hot top, a seating shoulder arranged to rest on the hot top, a portion arranged to extend downwardly from the upper end and into the bore of the hot top to below the desired level of molten metal therein, and a teeming orifice extending through both 80 said cover portion and said downwardly extending portion and disposed substantially centrally of both thereof. 90

4. A refractory cap for ingot mold hot tops comprising a cover portion arranged to cover the bore opening at the upper end of a hot top, a seating shoulder arranged to rest on the hot top, a portion arranged to extend downwardly a material distance into the bore of the hot top, and a teeming orifice extending through both said cover portion and said downwardly extending portion and disposed substantially centrally of both said portions, said downwardly extending portion having a lower surface rounded 100 outwardly from the teeming orifice thereof and inwardly from the bore of the hot top. 105

5. A refractory cap for ingot mold hot tops comprising a cover portion arranged to cover the bore opening at the upper end of a hot top, a seating shoulder arranged to rest on the hot top, a portion arranged to extend downwardly into the bore of the hot top to below the desired level of molten metal therein, and a teeming orifice extending 110 through said cover portion and said downwardly extending portion and disposed substantially centrally of both thereof, said downwardly extending portion having a lower surface rounded outwardly from the teeming orifice thereof and inwardly from the bore of the hot top. 115

In testimony whereof we have hereunto set our hands.

EUGENE L. MESSLER.
JAMES M. GUTHRIE.
